UNITED STATES PATENT OFFICE.

EDMUND H. LUNKEN, OF DENVER, COLORADO, ASSIGNOR TO THE LUNKENHEIMER COMPANY, OF CINCINNATI, OHIO.

DESIGN FOR A SIGHT-FEED LUBRICATOR.

SPECIFICATION forming part of Design No. 32,318, dated March 6, 1900.

Application filed February 1, 1900. Serial No. 3,648. Term of patent 14 years.

To all whom it may concern:

Be it known that I, EDMUND H. LUNKEN, a citizen of the United States of America, residing at Denver, in the county of Arapahoe, in the State of Colorado, have invented a certain new and original Design for Sight-Feed Lubricators, of which the following is a description, reference being had to the accompanying drawings, forming a part of this specification.

In said drawings, Figure 1 represents a front elevation of a sight-feed lubricator embodying my new design; Fig. 2, a side elevation thereof, and Fig. 3 a cross-section thereof on the line 3 3 of Fig. 2.

The essential and distinguishing characteristic of my novel design consists in the shape of the oil-reservoir A, which is approximately semicyclindrical in cross-section, as shown in Fig. 3, with its flat side *a* facing forward and its curved side *b* facing rearward and having a flat top and bottom and provided at its upper and lower ends with the forward extensions B C, receiving between them the sight-

feed and gage glasses D E, presenting the 25 appearance of two columns resting upon the lower extension C as a base and supporting the upper extension B. The fittings *c* for the glasses D E surround said glasses at their upper and lower ends, adjacent the extensions B C, and the extension C also receives upon its under side the fittings *d e* for the sight-feed regulating and drain cocks, while the upper extension B receives upon its upper side the filling-plug F.

The foregoing produces a sight-feed lubricator of striking design and appearance and radically different from the conventional forms heretofore employed.

Having thus fully described my invention, 40 I claim—

The design for a sight-feed lubricator as herein shown and described.

EDMUND H. LUNKEN.
